UNITED STATES PATENT OFFICE.

FRANK B. JOHNSTON, OF ROSELLE PARK, NEW JERSEY, ASSIGNOR TO AMERICAN SAFETY DEVICE COMPANY, A CORPORATION OF NEW YORK.

SCAFFOLDING DEVICE.

1,127,446.

Specification of Letters Patent.

Patented Feb. 9, 1915.

Application filed October 17, 1913. Serial No. 795,657.

To all whom it may concern:

Be it known that I, FRANK B. JOHNSTON, a citizen of the United States, residing in Roselle Park, Union county, New Jersey, ⁵ have invented certain new and useful Improvements in Scaffolding Devices, of which the following is a specification.

This invention has for its object to provide a hanging scaffold for use in the construction of buildings, which shall be firmly and removably secured in place on the frame of the building being erected, and which shall have the necessary strength and resistance to the strains of use to afford a safe structure for supporting the workmen and materials. For this purpose, the scaffold is provided with two superposed platforms, the additional platform serving to materially stiffen, steady and strengthen the entire structure. Also, the outriggers of the scaffold are secured in place by removable U-shaped clamps having swinging knuckles which engage the web of the outrigger and thereby secure the same reliably in place on the supporting beam of the building.

The hanging structure of the scaffold comprises vertical, dependent, supporting-members, platforms supported thereon, and a horizontal member connecting the vertical members and assisting in the support of the same and the platforms, and forming a guard-rail for the workmen.

In the accompanying drawing, Figure 1 is a front-view of a scaffold embodying the invention, Fig. 2 is a vertical section on line 2—2 of Fig. 1, on a larger scale, Fig. 3 is a perspective view showing the means of fastening an outrigger in place, Fig. 4 is a top-view of Fig. 3, and Figs. 5 and 6 show different forms of scaffold with double platforms.

Similar reference numerals indicate corresponding parts in all the figures.

Each of the outriggers 10 rests upon and is secured at its inner end to one of the horizontal beams 11 of the building, by means of a clamp comprising a U-shaped member 12 of bar or round iron threaded at its ends. The ends project upwardly ⁴⁵ above the plane of the outrigger. A cross-plate 13 connects the two ends, and above the plate suitable nuts 14 are screwed on the said ends, thus fastening the outrigger in

place against vertical movement from the beam 11. The friction of the plate 13 with the outrigger is in practice not sufficient to entirely prevent the lateral movement of the outrigger on the beam 11. For preventing such movement, swinging knuckles 15 are provided, pivoted one on each leg of the U-shaped member 12, in such position as when swung inwardly into locking position to enter between the upper and lower flanges and engage between them with clamping pressure the web of the I-beam forming the outrigger. One of the inner corners of each knuckle is rounded as shown at 16, in Fig. 4, so that the knuckle may be readily knocked into place by a hammer or other suitable tool. The end-faces of the knuckles are flat, as shown in Fig. 4, that is, tangential to the path of swinging movement of the knuckle, so that by the seating of these ends on the flat vertical web of the I-beam they resist displacement of the device. For closing the knuckles they are moved in the direction indicated by the arrows 18, in Fig. 4.

To the outriggers 10 are attached by suitable shackles, depending cables 20, each of which is secured at its lower end to a manually-operable hoisting-device 21 whereby the cables may be individually released or wound up and the floor-system of the scaffold thereby lowered or raised. The hoisting-device 21 is well known and requires no detail description.

The hoisting-devices 21 shown in Figs. 1 and 2 support double put-logs 22, and clamps 23, by which the planks 24 of the upper platform are secured into a connected platform, all as described in detail in my co-pending application Serial No. 784,332, filed August 12, 1913. From the put-logs 22 descend vertical supporting-members 25, preferably of bar-iron or steel, which support at their lower ends in like manner, below the upper platform, put-logs 26, to which the planking 27 of the lower platform is clamped by like clamps 28.

Each of the vertical supporting-members 25 is provided at a suitable point in its length with an eye 30 or other means for receiving and holding against disengagement a horizontal wire-rope cable 31, one end of which is secured to one of the members 25

2
by a rope-clamp 32 or other suitable means and the other end of which is similarly secured to another member 25. In case an intermediate portion of the scaffold from 5 any accident or other cause becomes unsupported, or insufficiently supported, in its descent it tends to draw downwardly the horizontal supporting cable 31, which the cable resists owing to its secure fastening at 10 its ends, and to its support in the eyes of the adjacent vertical members 25. The resistance to longitudinal collapse afforded by the two platforms between which the cable is located, together with the resistance to 15 vertical displacement afforded by the non-collapsible vertical members, creates a structure which in case of accident is self-supporting as to any individual part passed through by the horizontal supporting-cable. For 20 greater safety, the cables are arranged, one at the inner side and one at the outer side of the platform, as shown in Fig. 2, and they are located at such height above the platform that they act also as guard-rails in the 25 ordinary use of the scaffold by workmen, and afford a secure support which the workmen may grasp in case of dangerous tilting of the platform, whether vertically or horizontally.

30 In the modifications shown in Figs. 5 and 6 the structure is capable of being raised and lowered from the lower platform. In Fig. 5 the hoisting machines 40, are located on the upper platform 41, and operated by endless chains 42 depending through the upper platform to a point within reach of the workmen on the lower platform 43. In Fig. 6, the machines are located on the lower platform 43, the cables 20 descend thereto, 40 and the upper platform 46 is carried detachably on cross-beams 44 between suitable posts 45 rising from said lower platform, the upper platform in this case serving chiefly, or solely, as a roof for the protection of the 45 workmen on the lower platform.

Numerous embodiments of the invention have been shown and described. It is obvious that changes may be made therein without departing from the spirit of the invention as set forth in the claims.

I claim:

1. In a scaffolding device, a scaffold, outriggers above a plurality of separated points in the lengths of said scaffold, rigid supporting members at a plurality of separated points in the lengths of said scaffold, cables connecting said rigid supporting members to said outriggers, independent and independently operated hoisting mechanisms adapted 60 to raise and lower said cables, and an aux-

iliary supporting member intermediate and connecting said rigid supporting members.

2. In a scaffolding device, a scaffold, outriggers above a plurality of separated points in the lengths of said scaffold, rigid supporting members at a plurality of separated points in the lengths of said scaffold, cables connecting said rigid supporting members to said outriggers, independent and independently operated hoisting mechanisms 65 adapted to raise and lower said cables, and a flexible auxiliary supporting member intermediate and connecting said rigid supporting members.

3. A scaffolding device comprising an upper longitudinally non-yielding suspended platform, a lower longitudinally non-yielding platform, vertical non-collapsible members suspending the lower platform from the upper platform, said vertical members being connected to said platform at a plurality of separated points in their lengths, outriggers, supporting members for said upper platform, said supporting members being attached thereto at a plurality of separated points in the length of said upper platform, hoisting mechanisms for raising and lowering said supporting members independently, and auxiliary supporting members intermediate and connecting said vertical non-collapsible members, and intermediate 80 said platforms.

4. A scaffolding device, comprising an upper longitudinally non-yielding suspended platform, a lower longitudinally non-yielding platform, vertical non-collapsible members suspending the lower platform from the upper platform, some of said members being arranged at the inside and others at the outside of the platform, said vertical 95 members at the inside and outside being connected to said platforms at a plurality of separated points in their lengths, outriggers, supporting members connected to said outriggers for said upper platform, said supporting members being attached thereto at a plurality of separated points in the lengths of said upper platform, hoisting mechanisms for raising and lowering said supporting members independently, and auxiliary supporting members intermediate and connecting said vertical non-collapsible members, and intermediate 100 said platforms.

In testimony that I claim the foregoing as my invention, I have signed my name in presence of two subscribing witnesses.

FRANK B. JOHNSTON.
